UNITED STATES PATENT OFFICE.

PETER THOMSEN, OF CASSEL, GERMANY, ASSIGNOR TO THE SUPERHEATER COMPANY,
OF NEW YORK, N. Y.

FLUE SUPERHEATER.

Application filed March 1, 1926, Serial No. 91,463, and in Germany March 2, 1925.

This invention relates to a fire tube or flue boiler equipped with a superheater and consists in an arrangement wherein those tubes which are intended to receive superheater elements and which are hereinafter referred to as flues, are given different inner diameters and wherein these several flues are given such an arrangement relatively to each other that in at least one plane passed through a row of flues, flues of small diameter alternate with flues of larger diameter.

By this arrangement it is possible to obtain a higher superheat of the steam with a superheater located in the flues than has been possible hitherto, without materially decreasing the average efficiency with which the gases are utilized as compared with the former lower superheat. In addition, the tube sheet will not be materially larger for the same heating surface and free gas area than is the case where the flues are all of the same diameter.

Let us assume by way of illustration that in the case of a superheater element which extends into three flues of the same size lying in the same plane, the heating gases leaving the first flue are at a temperature of about 340° C.; those leaving the second flue are at a temperature of about 350° C., and those leaving the third flue are at a temperature of about 360° C. Under these conditions, we could obtain a superheat for the steam of about 360° C. under the most favorable conditions. If, however, these three flues are given different diameters, the flue containing the superheater loops carrying the wet steam being smallest and the one carrying the superheater steam being greatest, so that the gases leave the first flue at a temperature of about 300° C., the second flue at a temperature of about 350° C. and the last flue at about 400° C., then the average gas temperature under conditions similar to those of the first case will be about 350° C. The utilization of the heating gases is therefore approximately the same but the superheat in the second case would be about 400° C. or about 40° C. more than in the first case. This is brought about by the arrangement whereby the flues have different diameters and are grouped in the order indicated and the superheater elements are arranged in the flues in the necessary order.

The flues may be arranged in such sequence relatively to each other that, for example, one tube of small diameter or small free area alternates with one of larger diameter or free area, or on the other hand, also in such order that when three flues are arranged in a row, the middle flue is of normal diameter, the flue on one side has the greatest diameter and the flue on the other side the smallest diameter.

The number of flue diameters depends upon the question into how many flues a superheater element is to loop. The superheater elements are arranged in such manner in the flues, that the loops carrying the wet steam extend into the flues of smallest diameter and the loops carrying the hottest steam extend into the flues of largest diameter.

This flue arrangement is of particular applicability in the case of marine boilers in which anchoring or staying flues of greater wall thickness must be provided. In this case, the anchoring flues can be used for those flues which are to be given the smaller diameter.

The drawing represents several forms of the invention.

Fig. 1 shows the front view of a tube sheet of a locomotive boiler with flues of varying diameters with which a flue superheater is to be used.

Fig. 2 is a vertical longitudinal section through a row of tubes with superheater elements.

Figs. 3 and 4 are views corresponding to Figs. 1 and 2 of a locomotive boiler with flues of two different diameters intended to receive a superheater for smaller flues.

Figs. 5 and 6 are corresponding views of another form of my invention shown in a locomotive boiler and Figs. 7 and 8 show a form of flue arrangement and superheater in the case of marine boiler, Fig. 7 being a front view of the flue sheet and Fig. 8 being a horizontal section.

In the form of my invention shown in Figs. 1 and 2, the fire tubes of the usual inside diameter are designated by the reference character *a*. To accommodate the superheater, some rows of the fire tubes are replaced by larger flues. These larger flues which are to receive the superheater elements, are in accordance with the present invention, given different inside diameters. The group designated by *b* are given a large

diameter and a second group designated by the character *c* are given a smaller inside diameter. As will be clear from an inspection of the drawing, these two groups of flues *b* and *c* are so arranged relatively to each other, that the larger and smaller sizes alternate both in horizontal as well as in vertical rows. *d* is the header compartment for wet steam; *e* the compartment for superheated steam. The loops *f* and *f*¹ or *g* and *g*¹, extending from the wet compartment *d*, are first carried into the flues *c* of smaller diameter, are then reversed and are carried into the flues *b* of the larger diameter, are reversed in them and returned to the smokebox and the ends *h* and *h*¹, *i* and *i*¹ are connected to the superheated compartment of the header.

Figs. 3 and 4 illustrate the arrangement of flues having different internal free areas in the case of a locomotive boiler, which is intended to receive a superheater located in tubes of normal diameter. In this case also each tube *c* of small inner diameter is followed by one *b* of larger inner diameter, taking the tubes in vertical rows. The tube lengths *f* carrying the wet steam are secured to the wet steam compartment *d* by means of the intermediate or subsidiary headers *d'* and are here also inserted into the tubes *c* of smaller diameter, while the lengths conveying the superheated steam are located in the tubes *b* of larger diameter. The reference character *e'* designates the intermediate or subsidiary headers by means of which the superheated lengths *b* are secured to the superheated steam chamber *e*.

In the illustrative form according to Figs. 5 and 6 an arrangement is shown wherein there are three different sizes of flues for a locomotive boiler with superheater. The flues of usual diameter are designated by *a*, those of the largest inner diameter by *b*, and those of the smallest inner diameter by *c*. Between them there are arranged flues with an intermediate diameter, for instance, such diameter as is usual with large tube superheaters. These flues are designated by *c*². The flues vary as to their diameter both in the vertical as well as in the diagonal lines in the order mentioned. The superheater elements coming from the saturated steam chamber are successively carried through the flues *c*, *c*² and *b*, and the superheated ends are connected to the superheated chamber *e*. *f* and *h* are respectively the saturated and superheated lengths for the large row of flues in which the smallest flue *c* is located at the top, *f*¹ and *h*¹ are the corresponding lengths for the row of flues

in which the smallest flue *c* lies at the bottom.

In the example illustrated in Figs. 7 and 8 (marine fire tube boiler) the larger diameter tubes *b* and the smaller diameter tubes *c* again alternate, this time in horizontal rows. It is particularly advantageous in this instance to use the tubes *c* of smaller diameter as so-called anchoring flues, that is, to give them larger wall thickness. In this case also the arrangement of the superheater loops of the superheater elements is such that the loops *f* of the elements coming from the saturated chamber *d* extend into the smaller diameter flues *c* while the superheated steam loops *h* are located in the larger diameter flues *b*. Evidently the arrangement of the flues relatively to each other could be made the same as in the case of locomotive boilers, especially as shown in Fig. 3. However the arrangement according to Figs. 7 and 8 is particularly advantageous for marine boilers on account of the simpler arrangement of the superheater elements.

What I claim is:

1. In apparatus of the class described, the combination of a pair of flue sheets, flues connecting them, the flues being of two different internal diameters and so arranged that tubes of the two diameters alternate in rows running in one direction; superheater headers parallel and adjacent to one of the flue sheets, out of line with the flues, and at right angles to said rows of flues; and tubular superheater elements connected to said headers and each looping into flues of different diameters, the arrangement being such that the steam flows last through a loop in a large flue.

2. In apparatus of the class described, the combination of a pair of flue sheets, flues connecting them, the flues being of different internal diameters, tubular superheater units each comprising loops extending into flues of different diameters, and means to cause steam flow through the loops in a direction such that the steam flows last through a loop in a flue of the largest diameter used.

3. In apparatus of the class described, the combination of a pair of flue sheets, flues connecting them, the flues being of two different internal diameters, tubular superheater units each comprising two loops extending into flues of different diameters, and means to cause steam flow through the loops, the steam flowing first through a loop in a small diameter flue and last through a loop in a large diameter flue.

PETER THOMSEN.
